CLAIM

The ornamental design for a circulator cooker as shown and described.

DESCRIPTION

FIG. 1 is a top, front and right perspective view of a circulator cooker showing my new design;

FIG. 2 is a bottom, rear and left perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top view thereof; and,

FIG. 8 is an enlarged bottom view thereof.

The broken lines depict portions of the circulator cooker in which the design is embodied that form no part of the claimed design.

1 Claim, 8 Drawing Sheets
